(57) **CLAIM**

The ornamental design for an espresso coffee machine as shown and described.

DESCRIPTION

FIG. 1 is a front and left side perspective view of an espresso coffee machine in accordance with my new design;

FIG. 2 is a right-side elevational view thereof;

FIG. 3 is a front elevational view thereof;

FIG. 4 is a left-side elevational view thereof;

FIG. 5 is a top plan view thereof; and,

FIG. 6 is a rear elevational view thereof.

The broken lines in the figures are directed to environment and are for illustrative purposes only; the broken lines form no part of the claimed design.

The bottom plan view of the espresso coffee machine is not shown and therefore forms no part of the claimed design.
